CLAIM

The ornamental design for a cap, as shown and described.

DESCRIPTION

FIG. 1 is an isometric view of a top, front, and left side of an ornamental design for a cap;

FIG. 2 is a front elevational view of the cap of FIG. 1;

FIG. 3 is a rear elevational view of the cap of FIG. 1;

FIG. 4 is a right side elevational view of the cap of FIG. 1;

FIG. 5 is a left side elevational view of the cap of FIG. 1; and,

FIG. 6 is a top plan view of the cap of FIG. 1.

The dash-dash-dash broken lines are for the purpose of illustrating environmental structure and form no part of the claimed design. The dash-dot-dash-dot broken lines shown in the drawings define the boundaries of the claimed design.
